CLAIM

The ornamental design for an electronic torque wrench, as shown and described.

DESCRIPTION

FIG. 1 is a top perspective view of an electronic torque wrench, showing our new design;
FIG. 2 is a front elevation view thereof;
FIG. 3 is a rear elevation view thereof;
FIG. 4 is a side elevation view thereof;
FIG. 5 is another side elevation view thereof;
FIG. 6 is a top plan view thereof; and,
FIG. 7 is a bottom plan view thereof.

(Continued)

The broken lines shown in the drawings represent unclaimed subject matter and form no part of the claimed design.
